UNITED STATES PATENT OFFICE.

LANE E. WRIGHT, OF FAIRGRANGE, ILLINOIS.

ATTACHMENT FOR TELEPHONE-STANDS.

1,114,842

Specification of Letters Patent. Patented Oct. 27, 1914

Application filed December 19, 1913. Serial No. 807,736.

Be it known that I, LANE E. WRIGHT, a citizen of the United States, residing at Fairgrange, in the county of Coles, State of Illinois, have invented certain new and useful Improvements in Attachments for Telephone-Stands; and I do hereby declare the following to be a full, clear, and exact description of the invention, such as will enable others skilled in the art to which it applies to make and use the same.

The present invention is directed to improvements in an attachment for telephone stands, and has for its object to so construct an attachment of this character that the same can be easily and quickly attached to the conventional form of desk telephone.

A further object of the invention is to provide an attachment of this nature so constructed that when in place on a telephone stand the receiver may be placed in convenient relation to the ear, thus obviating the necessity of holding the receiver to the ear while telephoning.

With these and other objects in view, this invention resides in the novel features of construction, formation, combination and arrangement of parts to be hereinafter more fully described, claimed and illustrated in the accompanying drawing, in which:

Figure 1 is a perspective view of a telephone stand, showing the same equipped with the attachment. Fig. 2 is a transverse sectional view through the clamp employed for attaching the device to a telephone stand.

Referring to the drawing, the numeral 1 designates a telephone stand, of the conventional form, the same being provided with the usual transmitter 2, and receiver supporting arm 3.

The attachment comprises a clamp 4, which consists of curved jaws 5, said jaws being adapted to clampingly engage the stand 1, and is held in its proper position thereon by the clamping bolt 6 which is passed through the flanges 7 of the jaws 5. The flanges 7 terminate at their outer ends in channel members 8, the channels of which are for receiving the plate 9, said plate being firmly held in its proper adjusted position by the clamping bolt 6, which as before stated serves to clamp or attach the device to the telephone stand. The upper end of the plate 9 terminates in a forwardly extending horizontally disposed arm 10, the free end of which is provided with a lon-

gitudinal slot 11, the purpose of which will appear later. An angle lever 12 is provided and has its arm 13 pivotally connected to the bolt 14, which is supported by the plate 60 9. The arm 15 of the angle lever 12 has its lower end extended slightly below the plane of the arm 13, and is provided with a perforation 16 in which is secured one terminal 65 of a coil spring 17, the other terminal of which is connected to the ear 18 carried by the lower edge of the plate 9. The upper end of the arm 15 of the lever 12 terminates in a hook 19 which is designed to engage over the shank 20 of the receiver hook 3, and to hold the same in the position as shown in full lines in Fig. 1, and at which time conversation cannot be had over the line. The free end of the hook 19 terminates in an extension 21, which in turn 75 terminates in a curved off-set 22. The off-set 22 terminates in an arm 23, and it will be noted that by providing the off-set 22 that the arm 23 will clear the transmitter 2 when said arm is swung to its operative 80 or inoperative position.

Pivotally connected to the upper end of the arm 23 is a clamp 24 and by which the receiver 25 is supported. By pivotally connecting the clamp 24 to the arm 23 the receiver may be adjusted to suit the comfort of the user. Having its lower end pivotally connected to the forward end of the angle lever 12 is a bar 26, said bar being operable in the slot 11, said bar having a shoulder 85 27 formed in one edge thereof for engaging the inner end wall of the slot 11, thus holding the receiver 25 and its supporting elements in the position as shown in dotted lines in Fig. 1, and at which time the conversation can be carried on over the line. The upper end of the bar 26 is provided with a button 28 which is designed to be engaged by the user to force the bar downwardly so that the shoulder 27 thereon will operate to 90 hold the receiver in the position as shown in dotted lines. Upon disengagement of the shoulder 27 from the end wall of the slot 11, which is accomplished by swinging the arm forwardly the spring 17 will cause the angle lever 12 to rock so that the hook 19 will engage over the shank 20 of the receiver hook, thus automatically cutting off conversation 105 over the line.

From the foregoing description it will be 110 apparent that an attachment for telephones has been provided which may be easily and

2
quickly applied to a telephone and adjusted so that the receiver arm will be held in its locked position when the phone is not in use and readily released to unlock the receiver hook and simultaneously position the receiver in convenient relation to the ear of the user, thus leaving the hands of the user free to make notes.

What is claimed is:—

- 10 1. In combination with a telephone stand of an attachment comprising a clamp for engaging the stand, an angle lever pivotally supported by the clamp, one arm of said lever terminating at its upper end in a hook for normally engaging the receiver hook to hold the same depressed, said hook terminating in an arm, a receiver pivotally supported by the upper end of the last named arm, and means for rocking the angle lever to move 20 the hook from engagement with the receiver hook, thereby shifting the receiver, means to lock the hook in said position and means to automatically return said hook when said last mentioned means is released.
- 25 2. In combination with a telephone stand, of an attachment comprising clamping jaws adapted to engage the stand, channel mem-

bers carried by the clamping jaws, a plate clampingly engaged between the channel members, a horizontally disposed arm carried by the plate and having a slot formed in one end thereof, an angle lever having its horizontal arm pivotally supported by the plate and its vertical arm terminating in a hook for engaging the receiver hook to hold the same depressed, said hook terminating in an arm, a receiver pivotally supported by the upper end of said arm, a bar operable in the slot and having its lower end pivotally connected to one end of said horizontal lever arm, a shoulder carried by the bar and coöperating with the slot to hold the hook from engagement with the receiver hook when said bar is depressed, and means connecting the plate and vertical arm of the angle lever to swing the hook into engagement with the receiver hook when the bar is released.

In testimony whereof, I affix my signature, in the presence of two witnesses.

LANE E. WRIGHT.
